UNITED STATES PATENT OFFICE.

JOHN RAU, OF INDIANAPOLIS, INDIANA.

GLASS-BLANK-PRESSING MECHANISM.

1,159,992.

Specification of Letters Patent. Patented Nov. 9, 1915.

Application filed January 30, 1914. Serial No. 815,410.

To all whom it may concern:

Be it known that I, JOHN RAU, a citizen of the United States, and a resident of Indianapolis, county of Marion, and State of Indiana, have invented a certain new and useful Glass-Blank-Pressing Mechanism; and I do hereby declare that the following is a full, clear, and exact description thereof, reference being had to the accompanying drawings, in which like letters refer to like parts.

The object of this invention is the manufacture of bottles and like hollow glassware, particularly those of large capacity, without injuring the mouths and necks of the bottles and smoothly and perfectly finishing them.

Heretofore usually the lift over ring only finished the top edge or mouth of the bottle and the plunger finished the inside of the neck thereof. Any variation of the amount of glass made a difference in the distance which the plunger traveled. The end of the plunger slightly chilled the glass in the neck, but the lower portion of the blank was heavier and hotter and upon the removal of the ring and plunger or the blank being transferred to the blow mold from the lift-over, the top edge of the mouth of the bottle would sink and would be drawn by suction so as to leave a hole or recess in the inner surface of the neck just below the mouth which left the neck irregular in forming and provided with projections which would cut the corks. Another difficulty in the devices in use has been that the glass is liable to adhere to the ring and plunger and during the withdrawal the glass is pulled out of shape and to some extent out of the blank mold. One feature of this invention consists in providing a drop finish ring so mounted in connection with the plunger mounting means that said ring will rest upon the top of the mouth of the blank which has been formed in a mold and linger thereon for a time after the plunger has begun to withdraw from the mold or glass blank therein; and after said drop finish ring has performed the function of holding the mouth of the glass blank down in the mold while the withdrawal has been started, said ring is lifted by the plunger mounting mechanism from the mouth of the glass blank and the lift-over surrounding the neck of the blank. Preferably said ring is held in its lower position by gravity and is connected with the plunger mounting means by

headed screws or bolts projecting loosely therethrough and long enough to allow said ring to remain in its down position until after the plunger mechanism has moved upward somewhat during the withdrawal of the plunger.

Another feature of the invention consists in combining with said drop finish ring, a sleeve connected with the plunger mounting mechanism and adapted to project said ring and serve as a mold for forming the throat of the glass blank, and a plunger movable through said sleeve and independently thereof for entering the glass in the mold and not only making a blow opening in the blank, but forcing the glass up around said sleeve and within the lift-over and against said drop finish ring for forming the neck and mouth of the glass blank. In such construction the plunger has preferably an initial withdrawing movement preceding the withdrawing movement of the sleeve and the sleeve has a withdrawing movement preceding the withdrawal of the drop finish ring.

The foregoing arrangement and mode of operation thereof prevent malformation of the inner surface of the neck of the bottle by reason of the slow withdrawal of said plunger sleeve and prevent the tendency of the glass in the neck of the bottle to follow said sleeve during its withdrawal.

The full nature of the invention will be understood from the accompanying drawings and the following description and claims.

In the drawings, Figure 1 is an elevation of the upper part of a press mold, the lift-over thereon, and with a plunger mechanism above and in idle position and with the lower part thereof in central vertical section. Fig. 2 is a central vertical section through the upper part of the press mold and lift-over and the lower part of the plunger mechanism, showing the position of the parts during operation, after the initial withdrawal of the plunger and before the plunger sleeve has started to withdraw, parts being broken away. Fig. 3 is a similar section showing the parts with the glass in the mold in their condition and positions when the drop finish ring has started down on the lift-over. Fig. 4 is the same showing the condition of the parts after the plunger has been actuated. Fig. 5 is the same showing the parts in position after the plunger and plunger sleeve

have both withdrawn but before the drop finish ring has been withdrawn.

There is shown in the drawings a press mold 10 and a lift-over 11 which may be of any usual type. The lift-over has a central ring formed so that it constitutes a mold section for the outer surface of the neck of the bottle, and to help form the mouth of the bottle there is an annular recess 12 in the lift-over surrounded by an upward projection 13 having an upwardly extending lip 14 on its outer edge.

The plunger mechanism is provided with a vertical reciprocatory press rod 15 to which a cross bar or head 16 is secured. It carries two small rods 17 which are adapted to reciprocate through it and be held from downward escape by the nuts 18 on their upper ends. A spring plate 20 is secured to the lower end of said rods 17 and it is pressed downward by spiral springs 21 which surround the rods 17 and act between the cross head 16 and the spring plate 20 and yield to upward movement of the spring plate or downward movement of the cross head. A plate 22 is secured to the underside of the spring plate 20 by bolts or screws 23 or any other means and a plunger sleeve 24 extends down from said plate 22 and the plunger 25 is connected with the press rod 15 and operates through openings in the spring plate 20, the plate 22 and the plunger sleeve 24 loosely so that there may be some air leakage between the plunger 25 and said plates and plunger sleeve. A drop finish ring 30 is secured below and through the plate 22 by headed screws 31 which permit the drop finish ring to drop about three-eighths of an inch from the plate 22, as shown in Fig. 1, when the plunger mechanism is withdrawn from the press mold. The drop finish ring snugly surrounds the upper part of the plunger sleeve and, therefore, the plunger sleeve projects below the drop finish ring far enough to extend through the neck of the bottle substantially. The glass blank 35 is formed to mold the throat of the glass article and has a shoulder 26 at the upper end which co-operates with a recessed shoulder 37 of the surrounding drop finish ring so as to correctly form the top of the mouth of the bottle, as shown in Fig. 2. The lower portion of the drop finish ring is ring-like and fits in between the mouth of the bottle and the lip 14 and rests on the lift-over. Normally when the springs 21 are extended to their limit permitted by the rods 17, the lower end of the plunger 25 projects to the lower end of the surrounding plunger sleeve 24, as shown in Fig. 1.

The operation is as follows: After the glass has been placed in the blank mold and the lift-over placed thereon and shut and the glass cut off, the lever of the press, not shown, is operated. Ordinarily the glass 35

does not fill the lift-over part of the mold, but is substantially as shown in Fig. 3. As the plate 20 descends the loosely suspended drop finish ring 30 engages the top of the lift-over and the plunger sleeve 24 enters the mold opening through the lift-over and then plate 22 comes down upon the drop finish ring 30 and the parts assume the position shown in Fig. 3. In the next step of the operation, the plunger 25 is forced downward to the position shown in Fig. 4 and forms the blow opening 46 and forces the glass up through the mold opening in the lift-over and around the plunger sleeve 24 and against the drop finish ring, as shown in Fig. 4. When the press lever, not shown, is released, the springs 21 elevate the plunger 25 out of the glass from the position shown in Fig. 4 to the position shown in Fig. 2. This upward movement of the plunger and plate 16 under the influence of the springs 21 kicks up the plates 20 and 22 and the plunger sleeve 24, thus kicking said plunger sleeve loose from the glass, the parts assuming then substantially the position shown in Fig. 5, with the withdrawal of the plunger sleeve started and the plate 22 elevated somewhat above the drop finish ring 30. Further elevation of the plunger mounting means lifts the drop finish ring up from the lift-over, as by that time the drop finish ring rests upon the heads of the screws 31 and further upward movement lifts said ring 30. When the plunger sleeve 24 is kicked up to loosen it from the glass in the lift-over, the drop finish ring still maintains its position on top of the glass and prevents the tendency of the glass to follow the sleeve.

The function of the plunger sleeve is to prevent the displacement of the glass in the mouth of the bottle which would result if the plunger 25 and sleeve were not separate and successively operated. The sleeve protects the mouth of the bottle while the plunger is being withdrawn and when the sleeve is withdrawn there is no suction to displace the glass and the drop finish ring holds the glass down at the same time.

The invention claimed is:

1. Plunger mechanism for forming glass blanks for bottles including a plunger for forming the blow opening in such a blank, means for mounting and operating the plunger, a plunger sleeve surrounding the plunger, yielding means for mounting said sleeve in connection with the plunger mounting means which permits the plunger to move downward into the mold farther than the sleeve and after the downward movement of the sleeve has ceased and to begin its withdrawal movement before the beginning of the withdrawal of the sleeve, a drop finish ring surrounding said sleeve, and means for mounting said ring in connection with the sleeve mounting means so that in the down-

- ward position of said ring, it will rest on the top of the mouth of the blank and may have some vertical movement independently of the sleeve, whereby said sleeve and drop 5 finish ring will hold the glass of the blank down in place during the beginning of the withdrawal of the plunger and said ring will hold the glass of the blank down in place during the beginning of the withdrawal of the sleeve.
2. Plunger mechanism for forming glass blanks for bottles including a plunger for forming the blow opening in such a blank, means for mounting the plunger, a plunger 15 sleeve surrounding the plunger, means for yieldingly mounting said sleeve in connection with the plunger mounting means which permits the plunger to move downward into the mold farther than the sleeve and after 20 the downward movement of the sleeve has ceased and to begin its withdrawal movement before the beginning of the withdrawal of the sleeve, a drop finish ring surrounding said sleeve, and headed screws 25 connecting said drop finish ring with said sleeve mounting means so that said ring may have vertical movement independently of said sleeve.
3. Plunger mechanism for forming glass 30 blanks for bottles including a vertically movable cross head, a pair of rods reciprocable vertically through said cross head, a spring plate secured to the lower ends of said rods, springs surrounding said rods 35 and pressing against said cross head and plate, a plunger sleeve secured to said plate, a drop finish ring loosely surrounding said plunger, and means for loosely securing said ring to said plate so that the ring will have 40 some independent vertical movement.
4. Plunger mechanism for forming glass blanks for bottles including a press rod and
- cross head secured thereto, rods vertically movable through said cross head with nuts on their upper ends to limit their downward movement, a spring plate secured to the lower end of said rods, a spring surrounding said rods and pressing against said plate and cross head, a plunger sleeve secured to said spring plate, and a plunger extending 45 from said press rod through said spring plate and plunger sleeve.
5. Plunger mechanism for forming glass blanks for bottles including a plunger sleeve, a plunger operating through said plunger sleeve for pressing the blank to form a blow opening therein and force the glass up around said sleeve, and a drop finish plate surrounding said plunger sleeve and mounted 50 so as to have a limited extent of independent vertical movement.
6. Plunger mechanism for forming glass blanks for bottles including a press rod and cross head secured thereto, rods vertically movable through said cross head with nuts 55 on their upper ends to limit their downward movement, a spring plate secured to the lower end of said rods, a spring surrounding said rods and pressing against said plate and cross head, a plunger sleeve secured to said spring plate, a plunger extending 60 from said press rod through said spring plate and sleeve plunger, a drop finish plate surrounding said sleeve plunger, and means 65 for securing it to said spring plate which permits a limited amount of independent vertical movement of said drop finish ring.
- In witness whereof, I have hereunto affixed my signature in the presence of the witnesses herein named.
- JOHN RAU.
